[57] **CLAIM**

The ornamental design for a putting guide, as shown and described.

DESCRIPTION

FIG. 1 is a perspective view of the putting guide showing my new design;

FIG. 2 is a top view;

FIG. 3 is a side elevation view;

FIG. 4 is a bottom view;

FIG. 5 is an end elevation view;

FIG. 6 is an end elevation view;

FIG. 7 is a side elevation view;

FIG. 8 is another perspective view illustrating the moveable members in an extreme position;

FIG. 9 is another perspective view illustrating the moveable members in another extreme position; and,

FIG. 10 is a perspective view illustrating the moveable members placed in an opposite hand position.

Portions of the beam have been eliminated for ease of illustration in FIGS. 8 and 9.

FIG. 1.

FIG. 7

FIG. 9.
